UNITED STATES PATENT OFFICE

ALFRED CLEMENT COTY AND THOMAS EARL COTY, OF WATERTOWN, NEW YORK

BAG-BOTTOMING MACHINE

Application filed August 30, 1929. Serial No. 389,401.

Our present invention relates to bag bottoming machines, by which we mean devices for folding and pasting the ends of blanks cut off from a continuous paper tube. The present embodiment of the invention deals with lengths cut off a previously-prepared tube, which are stored in a magazine adjacent to the machine prior to the action of the apparatus illustrated in this case.

10. The machine which we have devised is especially adapted to forming in a single operation so-called "valve bags", in which one end of the bag is sealed and the other only partially so, and is particularly adapted for making these of the heavy paper required for cement or other materials of considerable weight and bulk, though not restricted in that respect. In these bags one end is closely sealed after being formed and folded, and 15 the other end is sealed in part only, leaving an opening by which the bag may be filled. This opening is afterwards closed in filling the bag. Generally speaking, these bags have been heretofore formed in separate machines, 20 one for each end; one end being closed, and the bag then transferred to another machine. Our present invention, therefore, embodies preferably the "tandem" location of mechanism for forming each end of the bag in the 25 way indicated, and an intervening mechanism between the apparatus closing one end of the bag and that for forming the other end, which receives the bags from the first machine and reverses them so that the open end is presented to the action of the second machine. 30 This involves as we believe a new method of operation, greatly accelerating the speed and increasing the output to an extent which has not heretofore been attained. Also, as we 35 point out in the claims defining our invention, it embraces mechanical combinations necessary for forming both the sealed bottom and the "valve" end of the bag in a single unitary structure, all the parts of which are so timed 40 and related as to co-operate in forming the completed product. So far as we are advised, this combination of mechanisms is new.

The accompanying drawings show an embodiment of our invention. Figure 1 is a 45 side elevation, partly broken away as to the

second one of the bag-forming mechanisms, and showing the gearing of the apparatus of the whole organization. Figure 2 is a side elevation upon a larger scale of the apparatus shown in the east end of Figure 1, with the 55 gears removed so as to show the bag-bottoming mechanism, and the magazine with its feeder. Figure 2a is a view of one end of the bag tube, showing the application of paste thereon. Figure 3 is a representation similar to Figure 2 of the west end of the parts shown in Figure 1, showing also particularly the reversing device or cylinder by the movement of which the bag is turned over to present its unfinished end to the second mechanism. 60 Figure 4 gives a plan view of the parts shown in Figure 3. Figure 5 is a detailed section upon the line 5—5 of Figure 2 of the creaser cylinder. Figure 6 is a section on the line 6—6 of Figure 3 of the reversing cylinder. 65 Figures 3a, 3b, 3c, are sketches of the bag in various stages of completion; and Figure 7 is a sketch of the bag complete.

Figure 1 shows at A the frame of the machine, which, as illustrated is cast in various units of different sizes and shapes, which are fitted together to make the complete machine, and secured in any desired way, as by dowel pins to secure precise positioning, and bolts or other fastening devices, which are not 70 shown but are well known to machinists. We have not deemed it necessary to describe all the different parts of the frame as they are sufficiently indicated in the drawing, and may be indefinitely varied. B is the magazine 75 containing the cut-off blanks B¹; B² is the feeding device for the blanks, which is illustrated in other Figures, but the construction of which is fully detailed in our Patent No. 1,668,761, bag feeding machine, dated May 8, 1928, and which it is therefore unnecessary to describe in detail. The parts indicated generically by the reference letter C are for forming the bottom of the bag, as shown, for example, in Figure 3a, and hereafter more 80 fully described. D indicates a cylinder for the creaser knives; E is a paste mechanism; F is the bottoming cylinder, which in some of its broader aspects is claimed in our Letters-Patent No. 1,742,174, dated December 31, 1929, 85 90 95 100

Serial Number 723,031, paper bag machine, filed June 28, 1924, and is described in detail and claimed in our pending application, 278-459, bag machine, filed May 17, 1928, and 5 which will be briefly described in connection with Figure 2. G indicates the reversing cylinder, more particularly described in connection with Figure 3. At this point the position of the bag is reversed, and it is started 10 through a second organization of instrumentalities, being turned over from the position shown in Figure 3a to that shown in Figure 3b.

The whole group of instrumentalities effecting this bears the reference letter G with various exponents. H is the co-operating cylinder for the creaser blades of the second apparatus. I is the bottom-forming mechanism of the second apparatus; K is the pasting mechanism, similar in its general character to the one marked E, differing slightly in the form of the shoe or pad which prints the paste at E² upon the bag, as shown in Figure 3c. After the application of the paste 20 and the folding over of the flaps, the bag is 25 in the shape shown in Figure 7, and passes out of the machine, being removed by any convenient conveying device, not illustrated.

Figure 2 shows an organization for forming the bottom of the bag, which is substantially like that shown in our application, Serial Number 278,459, already referred to. Here B² represents the bag-feeding device, shown in our Letters-Patent referred to, 30 which selects out the bottom bag from the pile shown at B1, and passes it into the machine. This device consists of the feeding blades b, b¹, which oscillate and pick off the bottom one of the bag blanks, which is then turned into 35 the machine by means of a revolving segment b², and a hook-shaped member B3, the feeding roll B⁴ co-operating with these to pass the end of the bag, having the thumb tag, as is usual, to the feed-rollers, C, C¹. The bag 40 then passes on to roll C², where the upper flap is engaged by the pin c¹ and the lower flap by the hook c² upon the roll C⁷. This hook is operated by the stationary cam C⁸, and holds the lower flap of the bag until it is 45 brought around to be engaged by the roll C⁹.

In the meantime the link C⁴ operates a finger C⁶ by means of a crank-arm C⁵ so that the finger holds open the flap which has been pulled open by means of the pin c¹; the crank-arm C⁵ is operated by the link C⁴ by means of the cam-roller c operated by the rotary cam C³ so that the motion of the finger C⁶ is regulated to hold open the upper side of the bag, while the finger C⁶ moves down at such a rate 55 as not to tear the bag, while still holding it open; when the roll C⁹ engages the bag, the finger is practically in alinement with the opening between the rolls C⁷, C⁹, and the bag easily slides off it, after which the finger C⁶ is 60 returned to its illustrated position. All this

is fully described in our application, S. No. 278,459, referred to and need not be detailed further. The bag continues its course between the feed-rolls C¹⁰, C¹¹, until it is engaged by the cylinder D and the belts or 70 tapes L, L¹. These tapes are in pairs on opposite ends of the cylinder as indicated in Figure 4. The construction of this cylinder D, as indicated also in Figure 5, is identical with that of the cylinder H in the apparatus for forming the second closure of the bag. In general, it consists of the cylinder D and the cross-arm D¹, these being secured together by 75 adjusting devices d, which permit the adjustment of the pads or slot-carrying parts D² upon the ends of the arm D¹ with reference to the creaser-blades and the other slot bars D³, D⁴. The purpose of this adjustment is to enable these pads to register with the knives K², K¹, consisting of arms carrying 80 creaser-blades for forming and turning up the flaps, which are to be folded by the cylinder F.

A second one of these knives or creaser-blades K¹ registers with the slot-carrying 90 bar D³, carried by the cylinder D; after the flaps are creased in this way, the bag passes on and is engaged by the belts L, L¹. The belt L is kept taut by a belt-tightener L³ of common form, and belt L¹ is similarly 95 tightened by such a device marked L², at the top of Figure 2. Of course these belts or tapes are run upon suitable guide-rollers, as is well understood.

While passing the cylinder D, paste is 100 printed on the closure of the bag, as shown at c¹, Figure 2a, by means of the pad e carried upon the roll E¹ of the paste-printing mechanism E. The pad e takes paste from a feeding roller E², which is carried upon a spring-operated arm E³, and revolves in the paste-tank E⁴. As will be observed the shape of 105 this paste-pad is such as to make a complete closure of the bag B¹ when the flaps are folded over.

Passing on from the cylinder D and the creaser-blades K¹, K², between the belts L, L¹, the bag engages with the folding cylinder F, which carries two sets of folding blades F¹, F², and F³, F⁴, so that two bags 110 may be operated upon at the same time by the single cylinder. A bag is shown with the flaps b³, b⁴, projecting between the disks, which constitute this cylinder, so called for convenience, the construction being particularly described in our application 278,459, 115 already referred to.

The blade F¹ presses down upon the flap b⁴ by a movement which first folds over the flap, and then presses it down and holds it in 120 place until the flap b³ is similarly folded over and held down by the blade F², the timing being such that the blade F¹ is withdrawn just as the second flap is folded over. These 125 blades are controlled in their action by the 130

stationary cams F^6 , F^6 , and are operated by cam-rollers running upon the edges of these cams, and also by others in grooves f^1 , f^2 , in their cam-faces. The positions of the cams 5 are maintained by bars F^7 , only one of which is shown, and there is the usual adjusting device F^8 .

After leaving the cylinder F the bag passes on between the tapes L, L^1 , and the rollers 10 l^1 , l^2 , l^3 .

Figure 3 shows the co-ordination of this reversing mechanism with the means for forming the closed end of the bag, and also with that for forming the valve end. Figure 15 3 should be read in connection with Figure 4.

The "cylinder" G is in reality composed of two disks spaced apart on a central shaft and which are tied together by crossbars g^{10} 20 against which the crank-levers G^3 , G^4 , clamp the bag and it is also provided with a stationary cam G^1 , having an adjusting device G^8 so that the timing of the arms G^3 , G^4 , may be regulated. Crossbars G^5 , G^5 , support over 25 the cylinder cylindrically-formed strips of metal which act to guide the bag. G^6 is a feed roller or disk, working in conjunction with the mutilated roll G^9 . This roll has two diameters in its different parts, one, g^5 , 30 being cut away, and the other, g^4 , registering with the roll G^6 .

A roll G^{10} is also provided having a fixed cam g^7 : the bell-crank lever g^6 , and the outer 35 end of the bell-crank is formed with a hook, the action of which is presently to be described. A feed-roller g^9 co-operates with the roll G^{10} ; and a roll G^{12} having two different diameters at different parts of the circumference, as illustrated, acts as a feed for the 40 bag.

The operation of the parts is as follows:—

When the bag leaves the belts L, L^1 , in the upper right-hand side of Figure 3, and passes down between the rollers G^2 and G, it is engaged by one of the hooks or bell-crank levers G^2 , and carried with the revolution of the roll between the rolls or disks G^6 , G^9 , the cut-away portion G^5 of the roll G^9 being then adjacent to the roll G^6 . The bag continues 45 to in this clock-wise direction until just as the end of it is about to pass between the rolls G^6 , G^9 , at which time the bell-crank lever, which holds it at the front end, is released by the cam projection g^1 . By this time the 50 larger diameter of the roll G^9 at g^4 has reached the roll G^6 , and engages the surface of the bag, the position of which is thus reversed as it is freed from the bell-crank, in the illustrated position. It should also be 55 stated that the bell-crank levers are operated by the projection g^2 on the cam G^1 , so that they are lifted just at the time when the bags engage with them in succession, and immediately running off the projection g^2 clamp the 60 ends of the bags tightly against the roll G.

By this time the hook g^6 has rotated until it is directly opposite the end of the bag as the rolls G^6 , G^9 , project the bag into the hook. This hook does not engage with any other parts of the machine, but is adjusted relative 70 to its engagement between the roll G^{12} and the roll C.

As soon as the bag has been pressed against the hook g^6 so as to locate the end of it definitely with reference to the succeeding operations, the cam-roller g^8 is operated by the high part of the cam g^7 , and the hook is removed from the end of the bag, permitting it to pass freely to the roll G^{12} , the larger diameter of which then engages with the roll 80 C at the definite point indicated by the designer. The entry of the bag to the rolls G^{10} and g^9 is thus timed correctly, after which cam-roller g^8 rides off the high spot of the cam, retiring the hook g^6 .

The roll C and its co-operating parts are precisely like the rolls C^2 , C^7 , shown in the east end of the machine in Figure 2. The finger C^6 is similarly operated, as is also the hook, and the bag passes on after having its 85 end opened, between the rolls C^7 , C^9 , C^{10} , C^{11} , and engages with the belt L and the creaser pad-roll H, which is also like the roll D of Figure 2. A paste-pad is shown at k^1 on the roll K for applying paste; but this pad, as 90 indicated at e^2 Figure 3^e, is so designed as to print paste upon only two sides of the opening, the effect being to leave the part of the bag marked b^5 unsecured so that the bag 95 may be filled, after which its flap is blown shut as the bag is filled.

In Figures 3 and 4 appears a guide rod G^{13} , one being on each side of the path of the bag; these act to straighten the bag at the time the grippers G^8 , G^4 let go and rolls 100 G^6 , G^9 take hold.

In Figure 5, I have shown a cross-section of the roll H, which is like the roll D of Figure 2, and of the cross-bar with its pad H^2 ; while the rim of the roll is marked H^1 , 110 and the adjusting bolts are marked H^3 .

In Figure 6 I have shown a cross-section of the reversing roll G; the reference characters being the same as shown in Figure 3, further 115 description of this figure seems to be unnecessary. Similarly a detailed description of Figure 4, the reference characters of which are the same as those of Figure 3, seems unnecessary.

The operation of the various gears co-ordinates the movements of the parts of the machines, a belt 1 driving a pulley from which all the gears take their motion and a longitudinal shaft 2 transmitting motion derived 120 from a bevel-wheel on the main pulley-shaft to a similar wheel on one of the gear-shafts of the second part of the apparatus, which forms the valve-end of the bag. These bevels 125 are cut away in Figure 1 to show the spur- 130

gears on the same shafts, but one set of them is shown at the left in Figure 4.

Many obvious changes may be made in the arrangements without departing from our invention.

5 While we have spoken herein of reversing the movement of the bag, and in a sense this is true, what happens is the reversal of the position of the bag relative to its movement through the machine; since obviously it proceeds from one end to the other of the apparatus in substantially uninterrupted progress.

10 We believe ourselves to be the first to provide a fully automatic apparatus which closes one end of a bag and then by a substantially continuous mechanical process forms the other end also, closing it to the desired extent and discharging the completed bag from the machine. We also believe ourselves to be the first to do this by "bottoming" the bag and then turning the bag end for end so that its open end is presented to the second bottommer, such reversal being effected by means maintaining positive mechanical engagement between the reversing mechanism and the blank during the passage, so that the blank is never free from control, and does not interfere with the others of the series; it is to be understood that we do not, by describing in this case a 20 magazine of previously prepared blanks, limit our invention to that construction.

25 What is claimed as new herein is:—

1. In machines for making bags, a magazine for tubular blanks, bottoming mechanism for closing one end of each blank in succession, feeding mechanism for passing the blanks successively from the magazine to the bottoming mechanism, bottoming mechanism for closing to a desired extent the other end of each blank in succession, and means intermediate of the two bottoming mechanisms for reversing the positions of the blanks successively with reference to the direction of motion through the apparatus; such means automatically maintaining positive engagement with each blank from its release by the first bottoming mechanism until it is engaged by the second.

2. In machines for making bags, means for feeding tubular blanks, means for closing one end of each blank, means for reversing the position of the blanks, such means positively engaging the blank during the entire reversal, means for feeding the blanks in reversed position, and means for closing the other ends of the blanks to a desired extent; the said several means being co-ordinated to act automatically upon a succession of blanks, as described.

3. Reversing mechanism in a bag-making machine comprising a cylinder, grippers carried thereby holding a bag-blank against the cylinder for travel in one direction, means for causing the bag to move in the reverse direction, and means for releasing the grippers when the last-named means acts, as described; whereby the bag-blank is turned end for end while continuing its progress through the machine, and is at all times positively engaged.

70 4. Reversing mechanism in a bag-making machine, comprising a cylinder, a gripper for holding a bag-blank against the cylinder, a cam for releasing the gripper and a spring for holding it closed, and a pair of gripping rolls for moving the bag in the opposite sense; the whole so timed that the gripper is released by the cam at the time the gripping rolls engage the bag blanks; whereby the blank is turned end for end relative to its progress through the machine.

75 5. In a machine for making bags, and in combination, means for feeding tubular blanks, bottoming mechanism closing one end of each of the blanks in succession, a reversing device for the blanks by which they are successively turned end for end with reference to their progress through the machine, the device comprising a cylinder revolving around a fixed cam upon a horizontal axis, grippers operated by the cam and holding the bag-blanks successively upon the cylinder, gripping rolls for engaging the open ends of the blanks at desired times, the cam-surface being formed to open the grippers to receive the blanks and to open them a second time to release the blanks when the latter are engaged by the gripping rolls, and bottoming mechanism for closing the open ends of the blanks to a desired extent.

80 6. As a unitary mechanism for making bags, a bag-bottoming apparatus for forming and closing one end of a tube forming a bag-blank, a second apparatus for forming and for closing to a desired extent the other end of the tube constituting the blank, and positive automatic mechanism for receiving the blank from the first apparatus and presenting it to the second in co-ordinated relation for such forming and closing; such mechanism positively engaging the bag-blank during the time of transfer from one bottoming apparatus to the other.

85 7. In a bag machine, means for closing one end of a bag-blank; means for closing to a desired extent the other end of the bag-blank; and positive automatic means in continuous engagement with the blank for transferring it from the first named means to the second and turning it end for end while so doing.

90 8. As a reversing mechanism for a bag-blank in a paper-bag bottommer, a cylinder, gripping fingers for receiving an end of the bag-blank, means for engaging the bag separate from the fingers and operative to reverse the movement of the bag, and means for releasing the fingers at the time the reversing means acts; the whole so timed and acting that the bag-blank is under continuous me- 130

chanical control during the entire reversing operation.

9. As a reversing mechanism for a bag-blank in a paper-bag bottomer, a cylinder, gripping fingers for receiving an end of the bag-blank, means for engaging the bag separate from the fingers and operative to reverse the movement of the bag, and cams and cam-rollers operating to release the fingers when the reversing means acts.

Signed at Watertown, in the county of Jefferson and State of New York this 22nd day of August, A. D. 1929.

ALFRED CLEMENT COTY.

THOMAS EARL COTY.
